UNITED STATES PATENT OFFICE.

GEORGE IGNATIUS MARLAND, OF DOOKIE, VICTORIA, AUSTRALIA.

WRENCH.

1,154,192.

Specification of Letters Patent. Patented Sept. 21, 1915.

Application filed July 9, 1915. Serial No. 38,917.

To all whom it may concern:

Be it known that I, GEORGE IGNATIUS MARLAND, a subject of the King of Great Britain and Ireland, &c., residing at Dookie College, Dookie, in the State of Victoria, Commonwealth of Australia, have invented 5 certain new and useful Improvements in and Relating to Wrenches; and I do hereby declare the following to be a full, clear, and 10 exact description of the invention, such as will enable others skilled in the art to which it appertains to make and use the same.

This invention relates to improvements in wrenches providing for adjustment of the 15 movable jaw relatively to the fixed one, by sliding, which takes less time than screwing. My construction provides for the removal of the movable jaw, leaving the fixed jaw on its stem usable as a hammer. It is common 20 to find wrenches used as hammers, but that often damages them.

In the accompanying drawings an embodiment of the invention is illustrated, but my claim is not restricted to the proportions 25 and designs shown.

Figure 1 is a perspective view of the wrench with a part broken away. Fig. 2 is a partly sectional elevation of a part of the stem having ratchet teeth and carrying a 30 casing on which is the movable jaw. Fig. 3 is similar to Fig. 2, but shows the movable casing adjusted for sliding. Fig. 4 is a sectional elevation at right angles to Fig. 3. Fig. 5 is a plan of parts in Fig. 1. Fig. 6 35 shows, partly in section, various details on a larger scale. Fig. 7 shows the implement after the slidable casing has been removed. In Figs. 1 and 5 a retraction pin is omitted.

In these views *a* is a stem or handle, carrying a fixed jaw or head *b*, having a hammer head *b*¹ of any suitable form. The nut or article to be gripped will be located between jaw *b*, the end, *a*², of the stem, and the movable jaw, *c*¹, which is part of a 40 low casing *c*, which has one or more bands *d* fitting around the stem and holding the casing in place but allowing of sliding motion.

To prevent the movable casing from slipping off the handle, a stop is provided, as a 45 spring tang *e* compressible into a recess or slot *f* in the handle *g* being a screw, rivet, or the like to hold the tang, or as in Fig. 7, a screw-pin *e*¹ can be adjusted higher or lower in a hole *f*² which is tapped in stem *a*, the 55 top, *f*¹, of the hole being enlarged so that it

will receive the head of the pin when it is required to disconnect the casing. Thus in each case a member is lowered to allow casing *c* to be removed; otherwise the casing, on reaching the stop, will travel no farther 60 toward the handle end.

Any suitable teeth are provided, as *h*, for engagement by a pawl or arm *i*, to lock casing *c*, to which arm *i* is pivoted as by pin *j*, against moving farther from jaw *b*, though 65 the casing can always move toward jaw *b* if the nut or object to be gripped allows room for jaw *c*¹ to come closer. The shape of the jaws is not necessarily suitable for nuts only.

Arm *i* is located in a chamber *k* within casing *c*, and as in Fig. 2 is normally pressed down by a suitable retractile spring *p*, shown as spiral, but not necessarily so. On retracting the spring, it takes the position 70 in Fig. 3. The means for retraction consists of a pin *o* which is attached to the arm *i* as seen in Fig. 6 by having its end passed loosely through a hole *i*² and enlarged. This pin is revoluble relatively to arm *i*, 75 and extends outside the casing through a circular recess *m*, through the lower wall of which is cut a rectangular slot *n*. A part of the pin under the head, as marked *s*, is also longer than it is broad providing a rectangular shank portion, and in the position of Fig. 2 part *s* fits down in slot *n* which is of similar size. When however the pin is lifted, the part *s* is raised out of slot *n*. The 80 pin should then be rotated so that part *s* will rest on the casing as in Figs. 3 and 6 so crossing slot *n*, and thus the raised pin cannot descend, the casing being then 85 slideable, so as to widen the distance between the jaws to fit a nut or article. As soon as the fit is effected the pin head, *r*, will be rotated until the part *s* registers with the slot *n* and enters the latter by the action of the spring, thus locking the arm *i* in position 90 in engagement with teeth *h*. The pin head 95 has preferably a part *w* of circular horizontal section.

Having described this invention what is claimed by Letters Patent is:—

A wrench, consisting of a shank, having a 105 fixed jaw, a handle end, and an intermediate series of ratchet teeth; a casing, including a jaw, slidably encompassing said shank, and having a rectangular slot formed in its upper wall; a pawl pivoted within said cas- 11

ing; a spring for causing said pawl to yieldingly engage said teeth; and a pin swiveled at its inner end to said pawl, and at its other end terminating in a rectangular shank portion, normally fitting within said slot, and having a rotatable operating head, whereby when said pin is elevated and rotated by said head, the said pawl is held dis-

engaged from said teeth, substantially as described. 10

In witness whereof I have hereunto set my hand in the presence of two witnesses.

GEORGE IGNATIUS MARLAND.

Witnesses:

GEORGE G. TURRI,
BEATRICE M. LOWE.
